DESIGN FOR AN ELECTRICAL METER

Clarence E. Mead, Chicago, Ill., and Ralph E. Sturm, Baltimore, Md., assignors to Bendix Radio Corporation, Chicago, Ill., a corporation of Delaware

Application February 18, 1938, Serial No. 75,239

Term of patent 7 years

To all whom it may concern:

Be it known that we, Clarence E. Mead and Ralph E. Sturm, residing, respectively, at Chicago in the State of Illinois, and at Baltimore in the State of Maryland, have invented a new, original, and ornamental Design for an Electrical Meter, of which the following is a specification, reference being had to the accompanying drawing, forming a part thereof.

The figure shown is a perspective view of the electrical meter embodying our new design.

The rear is substantially plain, while the bottom and other end portion are substantially like the top and end portion as illustrated.

We claim:

The ornamental design for an electrical meter, as shown and described.

CLARENCE E. MEAD.
